UNITED STATES PATENT OFFICE.

JOHN HORROCKS, OF FISHKILL LANDING, NEW YORK.

SPIKE.

SPECIFICATION forming part of Letters Patent No. 247,194, dated September 20, 1881.

Application filed April 28, 1880. (No model.)

To all whom it may concern:

Be it known that I, JOHN HORROCKS, of the village of Fishkill Landing, in the county of Dutchess and State of New York, have invented 5 a new and useful Improvement in Spikes, of which the following is a specification.

The invention relates to spikes for securing the rails of a railway-track to the sleepers.

I am aware of a former invention to combine with a spike a stud or projection extending downward from the elongated head or ear.

The spike heretofore in common use is a single plain spike, which is open to the following objections: first, it does not offer sufficient resistance to the vertical movement of the rail, for as the head of the spike sets on the flange or foot of the rail it is plain that the only resistance to the movement of the rail vertically is the force necessary to lift the spike up vertically; second, because, when loosened, it offers too little resistance to the movement of the rail laterally, and without a great deal of expense and attention becomes unsafe.

The object of my invention is to provide a spike which will offer more resistance, both laterally and vertically, to the movement of the rail, and which also can be readily removed when necessary.

The invention consists of a spike furnished 30 with an ear, said ear having a hole adapted to receive another spike.

In the accompanying drawings, in which similar letters of reference indicate like parts, Figure 1 is a view of my spike in its position against the rail. Fig. 2 is a detail view of the 35 ear and of the spikes.

The spike A has a nose or projection of the head, which sets on the foot or flange of the rail. On the side of the head of said spike there is an ear, R, which is forged in the same 40 piece with the spike and extends two inches, more or less. Said ear R has a hole adapted to receive another spike or screw, S.

The operation of the device is as follows: When the spike A is driven in the nose sets 45 on the foot of the rail and the ear R rests flat on the sleeper; then the spike S is driven in through the hole T in the ear R; and it will be seen that the vertical movement of the rail against the nose of the spike A acts tangentially on the ear R, and consequently against the strength of the two spikes. 50

What I claim is—

The spike A, having an elongated perforated head or ear, jointly with the screw or nail S, 55 substantially as described.

JOHN HORROCKS.
